GRATING OR VENTILATED FLOORING

Filed July 21, 1923

FIG 1

FIG 2

INVENTOR

Paul Leon Price

BY *P. L. Price*

ATTORNEY

UNITED STATES PATENT OFFICE.

PAUL LEON PRICE, OF MOUNT VERNON, NEW YORK, ASSIGNOR TO IRVING IRON WORKS COMPANY, OF LONG ISLAND CITY, NEW YORK, A CORPORATION OF NEW YORK.

GRATING OR VENTILATED FLOORING.

Application filed July 21, 1923. Serial No. 652,943.

My invention relates to ventilators or gratings of the type formed by a plurality of substantially straight or longitudinal strips and a number of intermediate or 5 spacing members separating the strips, the grating being adapted to be used for a variety of purposes, such for example, as on a sidewalk, or to form a floor. The object of this invention is to provide an improved 10 device of the above class which shall be simple in construction, and capable of forming a good tread surface or foothold in any direction.

The best form of apparatus embodying 15 my invention at present known to me is illustrated in the accompanying sheet of drawings, in which,

Fig. 1 is a plan view of a panel of such 20 grating or ventilated flooring; and,

Fig. 2 is an enlarged cross section on line 2—2 of Fig. 1, parts being broken away.

Throughout the drawings like reference 25 characters indicate like parts. In many of the gratings of the type described above which are in use today the spacing members extend longitudinally but are bent or curved in some particular fashion to keep the straight strips separated. Some of these 30 constructions have been criticised on the ground that there is liability of dirt collecting in the small angle between the longitudinal or straight strips and the spacing members where a spacing member comes in contact with the longitudinal strip. Besides 35 tending to avoid this criticism, my invention affords an excellent foothold for pedestrians, while combining with these virtues most of the advantages of the old constructions.

In the drawings 1, 1, indicate the longitudinal or substantially straight strips which are separated by the intermediate or 40 spacing members 2, also generally longitudinal in extent but bent to come in contact with the adjacent strips 1 at successive and uniform intervals. That portion of 45 each spacing member which is parallel with or contiguous to one of the strips 1 is indicated by the numeral 3. Instead of having 50 the portions of the spacing members intermediate of the sections 3, 3, form acute angles with the strips 1, I preferably bend the spacing member at each end of each parallel

portion 3 to a right angle as shown by the 55 portions 4 in the drawing, and thereby not only reduce the likelihood of particles of dirt becoming jammed at the immediate point of junction between the spacing members and longitudinal strips, but, since the 60 portions 4 are normal to the longitudinal strips, a better tread surface or foothold in some respects is provided for pedestrians walking along longitudinally of the grating. The portions 5 of the spacing strips which 65 lie between the aforementioned portions 4 are shown as being preferably disposed at an obtuse angle to the portions 4 and merging with portions 4 by proper curves, but it will be understood that these portions 5 may be arranged at any convenient or appropriate angle to the other portions of the 70 spacing members as may be desired. My grating may be formed of any suitable material, but is particularly adapted to be formed from bars of stock material from 75 which the strips 1 may be cut to the desired length and the spacing members 2 also cut and bent to their desired shape in a press or die. Where the spacing members and longitudinal strips are in contact at staggered 80 portions of the former they may be joined by means of welding or by means of bolts, rivets or other appropriate securing devices,—usually by rivets 6, 6.

From Fig. 2 it will be apparent that my 85 grating is made preferably with the spacing members of less depth than, but flush with the top of, the longitudinal strips, all in accordance with the arrangement shown and claimed in Patent No. 1,045,795, to Gustav A. Keller, granted November 26, 1912.

Another advantage resulting from the 90 construction above described arises from the ability of the middle portion 5 of the spacing member in each modification to flex 95 without distortion of the longitudinal strips, because the provision of more than two bends, in this case four bends, between successive points of contact with the longitudinal strips enables these bends to take up any 100 stress on the spacing member with less likelihood of distorting the longitudinal strips. The four bends referred to between centers of successive points of contact are the two 105 bends between portions 3 and 4 and the two bends between portions 4 and 5.

Having described my invention, I claim:

1. In a grating, a pair of longitudinal strips and a spacing member therebetween, the spacing member having staggered portions thereof parallel and in contact with said strips, other portions substantially normal to the first mentioned portions, and still other portions disposed at an obtuse angle to said second mentioned portions of the spacing member.
2. In a grating, the combination with a plurality of longitudinal strips, of a spacing member therebetween having portions thereof contiguous to said longitudinal strips at staggered points of contact, the spacing member between some of the successive points of contact with the longitudinal strips being provided with more than two distinct bends therein, the spacing member adjacent a contact portion being disposed at a greater angle to said longitudinal strips than is the central portion of the spacing member between the said successive points of contact with the longitudinal strips.
3. In a grating, the combination with a plurality of longitudinal strips, of a spacing member therebetween having portions thereof parallel with and secured to said longitudinal strips at spaced staggered portions of contact, the spacing member between successive contact portions being provided with at least four bends therein, the central portion of the spacing member between successive contact portions being disposed at a smaller angle to the parallel portions than its end portions contiguous with these parallel portions.
4. A floor grating comprising in combination longitudinal strips and spacing members between said strips, the spacing members being contiguous to the strips for short lengths, other portions of the spacing members at each end of said short lengths or contiguous portions being disposed substantially normal to said strips, and yet other portions of the spacing members between said contiguous portions or short lengths being disposed at an acute angle to said strips but at an obtuse angle to the second mentioned or normal portions of the spacing members.
5. A grating comprising a number of uniformly spaced longitudinal strips and a plurality of spacing members having portions thereof substantially normal to one another and a third portion to said member longer than one of said first mentioned portions and lying between pairs of said normal portions.
6. A grating comprising longitudinal members and spacing members bridged between the longitudinal members, the spacing members comprising staggered portions parallel with the longitudinal members, a sharp and substantially right angled bend at each end of each of the parallel portions, another

portion having two bends therein and joining pairs of said right angled bends.

7. A floor grating comprising longitudinal strips and spacing members therebetween and contacting with the longitudinal strips along staggered parallel portions, said spacing members comprising portions substantially normal to and at each end of said parallel portions connecting said normal portions, two of said spacing members being joined with a longitudinal strip in the same portions of its length.

8. In a grating, the combination with a plurality of longitudinal members, of spacing members between the longitudinal members, said spacing members having portions contiguous with and substantially parallel to the longitudinal members, another portion normal to and at each end of said contiguous members and of not greater length than one-half the distance between the longitudinal members, and still other portions connecting said second mentioned portions.

9. In a grating, a plurality of longitudinal members, a spacing member between said longitudinal members, portions of the spacing member being contiguous with and secured to opposite faces of the longitudinal members, a second portion of the spacing member being substantially normal to a first mentioned portion at an end thereof and a third portion of the spacing member being spaced from the longitudinal members, and connecting adjacent ends of two of said second mentioned portions.

10. A grating comprising a plurality of uniformly spaced longitudinal parts and other parts disposed between said longitudinal parts, said other parts comprising staggered portions having their faces contiguous with the longitudinal parts, second portions substantially normal to the staggered portions at at least one end thereof, and a third portion connected to an end of a second portion and angularly disposed with respect to the first two mentioned portions.

11. In a floor grating, the combination with a plurality of longitudinal strips, of spacing members arranged between said strips and secured thereto, each of said spacing members having substantially parallel and staggered portions adjacent said longitudinal strips where the spacing member is secured to the longitudinal strips, other or second portions of the spacing member being sharply bent away from the longitudinal strip at each end of the parallel portions, these second mentioned portions extending only part way across the space between the longitudinal strips, and still other or third portions of the spacing member arranged at an angle to and connected with the second mentioned portion at each end of the third mentioned portions.

PAUL LEON PRICE.
